UNITED STATES PATENT OFFICE.

OSCAR DINGFELD, OF BROOKLYN, NEW YORK.

HAND-CASE FOR LADIES.

1,386,848.

Specification of Letters Patent. Patented Aug. 9, 1921.

Application filed January 22, 1921. Serial No. 439,228.

To all whom it may concern:

Be it known that I, OSCAR DINGFELD, a citizen of the United States, residing at Brooklyn, in the county of Kings and State 5 of New York, have invented a new and useful Hand-Case for Ladies, of which the following is a specification.

My invention relates to improvements in hand cases for ladies, which are now commonly made of a frame and cover plates soldered together, and my improvement consists mainly in obviating the necessity of soldering by the construction of the hand case hereinafter more fully described, and it 15 also contains other novel features herein-after more fully described.

The objects of my improvement are:

First: To make a hand case for ladies, in which each frame or basil is connected to 20 the corresponding cover plate by a mechanical joint without soldering.

Second: To enable dissimilar materials to be used for the frame and for the cover plate, whereby, while the frame is made of 25 a material strong enough to stand the strain of repeated opening and closing of the case, the cover plate may be made of a material which will permit ornamentation by delicate engraving, lacquering or enameling.

Third: To make provision for strengthening the basil or frame in the vicinity of the hinge to prevent bending or undue straining of the hinge and the part of the frame adjacent thereto; and

Fourth: To have said hand case simple, durable and inexpensive.

I attain these objects by the hand case illustrated in the accompanying drawings or by any mechanical equivalent or obvious 40 modification of the same.

In the drawings Figure 1 is a section of my hand case on the lines A—C—B of Fig. 2, but omitting the lock or latch and sundry appurtenances of the case; Fig. 2 is a plan 45 of the lower half of the hand case; Figs. 3 and 4 are detail views on a larger scale of the left end and right end respectively of Fig. 1.

Similar numerals refer to similar parts 50 throughout the several views.

11 designates the annular basil or frame of the upper half of my hand case, which is shown as having its outer rim 12 curled over the edge of the cover plate 15; 13, 14

and 16 are respectively the frame, the outer 55 rim thereof and the cover plate of the lower half of my hand case.

The frames 11 and 13 may be made preferably of some metal, such as brass or steel, which is strong enough to stand the strain 60 of repeatedly opening and closing the hand case; but the cover plates 15 and 16 may be made preferably of some material such as aluminum, copper or celluloid, which is soft enough to permit delicate ornamentation by engraving, lacquering or enameling, or partly by one and partly by any other of the above processes.

Aluminum is particularly fit for this purpose, because it permits a superior engraving which stays white; but I do not restrict myself to any one metal or material, as sundry materials may be employed, as long as they are rigid enough to be self sustaining 70 against being collapsed by the handling of 75 the hand case.

The cover plate may also be made of some soft material which is not self sustaining and a metal support provided therefor.

As the basil or frame of my hand case is 80 of a different material from that of the cover plate, soldering is not feasible for joining the two together; I, therefore, propose to have the two connected by a mechanical joint, such as is obtained by curling the outer rim 85 of the basil or frame 11 or 12 over the edge of the cover plate 15 or 16.

The above joint is made extra neat and practically undiscernible by providing each 90 of the cover plates 15 and 16 with the shoulders 20 and 21, against which the edges of the rims 12 and 14 are nearly abutting, thereby making the appearance of continuity of the metal of the rims 12 and 14 with 95 that of the cover plates 15 and 16.

Another feature of my hand case is the stiffening rib 17 in the basil or frame 11, with the corresponding rib 18 in the frame 13, both in the vicinity of the hinge 19; each 100 rib is made in one with its basil or frame and extends through a part of the inner edge thereof, as is clearly shown in Fig. 2, thereby strengthening the frame near the hinge 19, and thereby preventing the bending or undue straining of the latter.

22 is a pair of ears for a chain to be connected to the hand case.

Many changes could be made in the details

of my hand case without departing from the main scope of my invention.

I do not, therefore, restrict myself to the details of my hand case as shown in the drawings; but I intend to include also all mechanical equivalents and reasonably obvious modifications of the same within the scope of my invention.

What I claim as my invention, and desire 10 to secure by Letters Patent is:

1. In a hand case the combination of a basil or frame and a cover plate of dissimilar materials, connected to each other by means of a mechanical joint, said basil being 15 of material strong enough to stand the repeated strain of opening and closing the case, and the material of the cover plate be-

ing adapted to permit delicate ornamentation thereon.

2. In a hand case an upper and a lower 20 basil or frames joined by a suitable hinge and a stiffening rib made integrally with one of said basils in the vicinity of said hinge, thereby strengthening the basil adjacent to said hinge and thereby preventing 25 the bending or undue straining of the hinge.

3. In a hand case the combination of a cover plate of self sustaining material and a basil or frame substantially encompassing the same, said cover plate and said frame 30 being of dissimilar materials and connected to each other by means of a mechanical joint.

OSCAR DINGFELD
